Primary Examiner — Robert M Spear*Assistant Examiner* — Ryan Harvey(74) *Attorney, Agent, or Firm* — John P. McGonagle(57) **CLAIM**

The ornamental design for a hand grip bridge, as shown and described.

DESCRIPTION

FIG. 1 is a top perspective view of a hand grip bridge showing my new design, wherein the partial view of the hand shown in broken lines illustrates environment only and forms no part of the claimed design;

FIG. 2 is a top view thereof;

FIG. 3 is a rear view thereof;

FIG. 4 is a bottom view thereof;

FIG. 5 is a front view thereof;

FIG. 6 is a right side view thereof; and,

FIG. 7 is a left side view thereof.

The broken lines illustrate environment that forms no part of the claimed design.

1 Claim, 3 Drawing Sheets(56)
